Attorney, Agent, or Firm—Gallagher & Kennedy*[57] **CLAIM**

The ornamental design for a light fixture, as shown and described.

DESCRIPTION

FIG. 1 is a perspective view of the light fixture showing my new design;

FIG. 2 is a front elevation view of the light fixture of FIG. 1;

FIG. 3 is a bottom plan view of the light fixture of FIG. 1; FIG. 4 is a right side elevation view of the light fixture of FIG. 1;

FIG. 5 is a top plan view of the light fixture of FIG. 1; and, FIG. 6 is a front elevation view of a further embodiment of the light fixture showing my design.

The left side of the light fixture of FIG. 1 is the mirror image of the right side elevation of FIG. 4 and is not separately shown. Broken lines in FIG. 6 represent a light fixture of the same design as FIG. 1 with either additional globes or no further globes intermediate the right and left end globes shown. The rear of the light fixture is plain and unadorned and is not a part of the claimed design.
